SHIPPING AND FILING BOX

Carlton L. Whiteford, Brooklyn, N. Y.

Application July 7, 1938, Serial No. 217,947

2 Claims. (Cl. 229—14)

This invention relates to an improved shipping and filing box.

The invention has for its general object the provision of a simple and inexpensive cardboard box adapted for shipping and filing rectangular flat articles and for spacing such articles slightly apart.

A further object resides in the provision of a box having a lining of corrugated material, preferably in a single piece, which corrugated material defines the inner bottom and opposite side walls of the box whereby the valleys between the corrugations afford guiding slots for articles placed in the box for shipment or filing.

15 A further object of the present invention resides in the provision of a simple and cheap box adapted for use in a shipping container for articles such as photographic lantern slides and which container is of such shape and configuration that it 20 is adapted for subsequent use as a filing box from which any one slide may be conveniently removed.

Further and other objects of the present invention will be hereinafter set forth in the accompanying specification and claims and shown in the drawings which show by way of illustration a preferred embodiment and the principle thereof and what I now consider to be the best mode in which I have contemplated of applying that principle. Other embodiments of the invention employing the same or equivalent principle may be used and structural changes made as desired by those skilled in the art without departing from the present invention and within the spirit of the appended claims.

35 In the drawings:

Figure 1 shows a perspective view of the complete box with a portion of the cover broken away to show the interior construction and to show the manner in which articles are received and retained in the box;

Fig. 2 is a detail sectional view taken substantially on line 2—2 of Fig. 1;

Fig. 3 is a view showing the inner corrugated lining and the manner in which it is shaped and formed prior to insertion in the body of the box;

Fig. 4 is a detail view taken substantially on line 4—4 of Fig. 3;

Fig. 5 is a perspective view partly in section showing the manner of construction; and

50 Fig. 6 is a detail sectional view taken substantially on line 6—6 of Fig. 5.

In the drawings, 10 (see Figs. 2 and 5) designates a set-up cardboard box of usual construction. 11 designates the customary cardboard box cover. 10a and 11a designate a glued-on paper

cover for the box and cover. The paper covering 11a may be provided with suitable advertising matter and instruction data, etc.

Referring now to Fig. 3, in this figure, 12 designates a flat sheet of corrugated material such as corrugated paper. The sheet is blanked out to proper size to form a lining for the box 10. It is then scored with two rows of scorings 13. Such scorings deform the corrugations downwardly and permit the bending up of the corrugated sheet into a general U-shape with sharp angles along the score lines. The ends of the corrugated sheet are also rolled down flat as indicated at 14 in Fig. 3. This rolled-down portion 14 provides a flat surface on which the wrapper may be glued. 15 After scoring the corrugated sheet in the manner just described, it is bent into a general U-shape and fitted down within the set-up cardboard box 10. As a final step, the upper margins 10b of the box wrapper 10a are folded over the portions 14 20 and glued thereto. This gluing operation secures the corrugated liner in position within the cardboard box. The box is now complete and ready for use. When the box is completed, it will be understood that the corrugated material defines 25 the inner bottom and opposite side walls of the box. The valleys and ridges of the corrugations on the bottom and opposite side walls of the lining are in alignment and accordingly the valleys afford guiding slots for articles of rectangular 30 shape, see for example the lantern slides generally designated 15 in Figs. 1 and 2. The box or carton may be used as a shipping container and after receipt, a customer may use the same box as a filing box for the articles. The ridges of the cor- 35 rugations serve to slightly space the articles apart. In this way protection is afforded to the articles during shipment and the spacing between the articles also facilitates the removal of any single slide or article when the box is used for filing purposes. The slight spacing between the articles facilitates inspection of designating indicia on the slides so that a selected slide can be picked out for removal.

40 I claim:

1. A shipping and filing box for the purpose described comprising a set-up cardboard box with a cover and including in combination the corrugated lining for the bottom and two opposite side walls of the box with corrugations extending in 50 alignment and across the bottom and facing inwardly to afford therebetween a plurality of guiding slots for the reception of a plurality of articles, said corrugations being scored to afford angle bending of the lining at the inner section of the 55

bottom and side walls of said lining with maintained continuity of corrugations, said corrugations of said lining being also flattened along the top marginal opposite edges, and a glued wrapper for the set-up box having the upper marginal edges folded over and glued to the flattened portions of the corrugated lining.

5 2. A box having a lining bottom and two opposite side walls thereof formed of corrugated material with valleys between the corrugations on

the sides and bottom in alignment for receiving and guiding flat articles, said corrugations on the sides and bottom serving to space one article from the next adjacent article, said corrugated material comprising a single piece of material of a U configuration having the corrugations adjacent the marginal top portions of the lining flattened for the purpose described.

CARLTON L. WHITEFORD. 10
